LONG LIFE CATHODE FOR ELECTRON TUBES

Dewey D. Knowles, Wilkinsburg, and George S. Evans, Turtle Creek, Pa., assignors to Westinghouse Electric & Manufacturing Company, East Pittsburgh, Pa., a corporation of Pennsylvania

Application November 27, 1937, Serial No. 176,852

2 Claims. (Cl. 250—27.5)

The invention relates to cathodes, and especially to cathodes for gaseous discharge devices.

An object of the invention is to provide a cathode having a reserve supply of emissive material to supplement the regular supply, especially when the regular supply is not sufficient for the load current being conducted through the discharge device.

Other objects and advantages of the invention will be apparent from the following description and drawing, in which the drawing shows a cross-section through a tube disclosing a preferred cathode therein.

The electron emission from any of the thin film cathodes and from the latest type of oxide-coated cathodes is known to be either directly or indirectly due to free barium in or on the surface of the cathode. This barium is ordinarily made available by diffusion from the core material either by decomposition of the coating due to heat or by electrolysis. The life of such a cathode is, therefore, limited to the length of time that this barium supply can be maintained. There are various factors which limit the amount of barium supply that can be provided in the ordinary type of oxide-coated cathode structure. If a thick coating of oxide is used to obtain more barium, the resistance becomes too high to be practical.

The invention concerns the idea of providing a reservoir of free barium that will provide an auxiliary supply of electrons especially when the usual supply is not sufficient.

In the drawing, we have disclosed a tube 10 having usually a gaseous filling 11 therein and an anode 12.

The cathode comprises a casing 26, preferably in the form of a thimble of metal, such as nickel or iron, having at the upper end a porous metallic block 24 having an opening 25. This block or top is preferably of sintered tungsten or of a metal having a porosity of the order of sintered tungsten. A piece of metallic barium 21 is placed in the bottom of this casing or thimble. The porous top 20 has electron-emissive material in its pores such as barium and strontium oxide and a suitable heater 22 maintains the porous top or block at a suitable electron emitting temperature which may be of the order of 900° C.

It will be noted that the top 24 has an opening 25 therein exposing the free barium 21 to possible bombardment. It is desired that a temperature of approximately 400° C. be applied to the free barium 21 in the bottom of the casing while the top of the casing is operated at a temperature of approximately 900° C. If the emission of the electrons from the top of the crater cathode is sufficiently good, the voltage drop will be less and not many positive ions will project to the bottom 10 of the casing and bombard the barium. If the emission decreases, however, the drop will increase and consequently, the number of high speed ions striking the barium pellet will increase. These ions sputter off the barium and 15 replenish the supply of barium at the crater opening 25. The advantage of the cathode structure shown is that the adjustment of additional electron emission is always instantaneous because there is no delay caused by the necessity 20 of some part changing its temperature.

Many modifications may be made in the form, number and arrangement of the various elements disclosed and their application to other types of tubes. Accordingly, no limitations 25 should be imposed upon the following claims except as necessitated by the prior art.

We claim as our invention:

1. Cathode structure comprising a casing, a top on said casing having a porosity of the order 30 of sintered tungsten, electron emitting material in said porous top, and barium within said casing, said top having an opening therethrough whereby said barium may be bombarded by ions from outside said casing having sufficient 35 velocity.

2. A cathode for an electrical discharge device comprising a casing enclosed except on the top side, the top side being of material having pores of the order of those characterizing sintered 40 tungsten and having an opening through it which has a diameter many times larger than said pores, a supply of an alkaline-earth metal within said casing positioned so as to be bombarded by ions entering said casing through said 45 opening.

DEWEY D. KNOWLES.
GEORGE S. EVANS.
